PISTON

David Bushby, Regina, Saskatchewan, Canada,
assignor to The Vacuum Air Pressure Company
Limited, Regina, Saskatchewan, Canada

Application January 15, 1940, Serial No. 314,004

8 Claims. (Cl. 309—11)

My invention relates to improvements in pistons and the principal object of my invention is to provide a device of the character herewithin described which particularly when used in association with internal combustion engines and the like, maintains for a longer period of operation a considerably higher compression sealing effect than has previously been obtainable in cylinders employing pistons of conventional design.

A further object of my invention is to provide a device of the character herewithin described wherein the elongation of the cylinder bore caused by the action of the piston is eliminated by a circumferential equalization of the piston wear.

A further object of my invention is to provide a device of the character herewithin described in which the necessity of conventional piston cam-grinding is avoided by a circumferentially uniform coefficient of piston expansion.

A further object of my invention is to provide a device of the character herewithin described wherein an automatic means is incorporated for maintaining the high compression assembly in proper contact with the cylinder wall, simultaneously preventing the leakage of compressed gases therebetween and the body of the piston.

A further object of my invention is to provide a device of the character herewithin described in which the conventional practice of installing new rings into the worn ring grooves of an old piston is eliminated by the provision of a replaceable high compression assembly retaining means.

A further object of my invention is to provide a device of the character herewithin described, which will outlast the conventional piston in operation, maintain a constant highly efficient compression sealing effect to the end of its life and render itself economical to manufacture and repair.

With the above more important objects in view and such other minor objects as may appear as the specification proceeds, my invention consists essentially in the arrangement and construction of parts all as hereinafter more particularly described, reference being had to the accompanying drawings, in which:

Figure 1 is a vertical cross-sectional elevation of my piston and high compression assembly showing the same in a new or unworn condition.

Figure 2 is a sectional elevation along the line 55

2—2 in Figure 1, but showing my compression assembly as being partially worn.

Figure 3 is a perspective illustration of one of my annular springs incorporated in the subject matter of Figures 1 and 2.

In the drawings like characters of reference indicate corresponding parts in the different figures.

My piston 1 is provided with a lateral wall 1' 10 of substantially a smaller diameter than the bore of the cylinder walls 2 to accommodate my high compression assembly 3 therebetween. The latter is positioned subjacently to an annular flange 4 formed by the piston head 1'' and its 15 various constituents are retained in position by means of the snap rings 5, 6, 7 and 8, engaging annular recesses 5', 6', 7' and 8' provided in the piston wall 1', the rings 5, 6, 7, and 8 being what I call "groove-forming rings" inasmuch as 20 they act as one of the annular projecting boundaries of the adjacent groove.

My high compression assembly 3 includes a pair of split, interlocking compression rings 9 and 10. The former has the upper edge 9' there- 25 of in engagement with the flange 4, and is provided with a circumferential recess 11 designed to receive a split compression seal ring 12.

The adjacent edges of the rings 9 and 10 are complementarily rabbeted as at 13 to facilitate 30 interlocking and the ring 10 has its lower edge recessively chamfered to provide an undercut recess 14, a cuneiform cross-sectional configuration clearly apparent from the referred to figures of the accompanying drawings.

35 A pair of projecting pins 15 and 15' are installed in suitable apertures provided in the wall 1' and the flange 4 respectively on the diametrically opposed sides of the piston 1 and engage the slots of the split rings 9 and 10 as best illus- 40 trated in the accompanying Figure 2.

The aforementioned snap-ring 5 retains the interlocked ring assembly 9, 10 and 12 thus formed in position against the piston flange 4, yet permits any diametrical expansion thereof 45 as may be imparted to it by a spring pressed sliding sleeve 20 detailed hereinafter.

An intermediate annular skirt 17 is freely mounted upon the piston wall 1' essentially medially of the length thereof and in spaced relationship in respect to the lower compression ring 10. A pair of the aforementioned snap rings 6 and 7 engage the upper and lower edges of the skirt 17 respectively and the latter is split in a similar manner to the compression rings 9, 50 10 and 12.

The upper and lower edges of the skirt 17 are chamfered similarly to the compression ring 10 to provide undercut recesses 18 and 19 of a cuneiform section. A pair of annular spring pressed sliding sleeves 20, 20' are interposed between the recess 18 of the skirt 17 and the recess 14 of the ring 10 in the manner now to be described.

Each of the sleeves 20, 20' has one edge 21 thereof stepped outwardly from the intermediate surface 21 of the sleeve to provide an annular projecting flange 22. The latter are in a complementary engagement with the aforementioned cuneiform recesses 14 and 18 respectively and spaced apart by a spring means 23.

The spring means 23 may assume the form clearly illustrated in Figure 3 of the accompanying drawings and comprises a split annular steel spring 24 alternatively depressed and elevated as at 25 and 25' respectively, to produce a ring member of the desired width and resiliency.

The spring 23 engages a pair of annular grooves 26 and 26' formed medially in the opposing extremities or edges of the sleeves 20, 20' respectively, and a freely mounted spacing ring 27 is loosely interposed therebetween to prevent an actual contact thereof.

The inner surfaces of the sleeves 20, 20' are stepped back as at 28 so that the intermediate surfaces 21' partially overlap the snap rings 5 and 6, and in this connection it will be seen that a space 28' exists between the riser 29 and the opposing edges of the snap rings 5 and 6 when the assembly is unworn as per the accompanying Figure 1.

Positioned immediately below the skirt 17 I provide an annular sleeve and spring arrangement to the aforementioned sleeves 20, 20', the spring 23 and the spacing ring 27, namely an additional annular spring pressed sliding sleeve 29', a spring means 30 and a spacing ring 31, all above parts being identical in structure to those already detailed and hence requiring no further explanation.

The spring 30 at the lower points of contact thereof engages an annular groove 32 similar to the previously mentioned grooves 26 and 26' formed in the upper edge of an annular retaining ring 32'.

The latter is retained near the lower extremity of the piston wall 1' by means of the snap-ring 8 and is provided with an annular circumferential groove 33 designed to receive a split oil ring 34.

When my piston and high compression assembly A is placed in operation, it will be observed that the sliding sleeves 20, 20' and 29 under the actuation of the spring means 23 and 30 will constantly urge the interlocking compression ring assembly 9, 10 and 12 outwardly against the cylinder walls 2 under progressive conditions of wear.

The above feature combined with the arrangement for retaining the separated ends of the compression rings diametrically opposed will materially assist in maintaining true concentricity of the cylinder bore. Furthermore, the cam-grinding process now employed in the manufacture of the conventional pistons becomes unnecessary in my invention, since the piston wall 1' is of a uniform longitudinal cross-section throughout its perimeter and is therefore subject to a balanced coefficient of expansion under the presence of heat.

Finally, when after a considerable period of usage it becomes necessary to replace my high

compression assembly 3, the installation of new snap rings 5, 6, 7 and 8 will retain such assembly in its new or original position upon the piston wall 1' and thus eliminate the now common practice of installing new piston rings into the loose and worn grooves of the piston.

Since many modifications can be made in the invention herein described and since the accompanying drawings have been prepared only to illustrate the relative arrangement and interaction of parts and not with regard to accuracy of dimensions for manufacturing purposes which in view of this disclosure I consider to entail merely mechanical skill together with the skill of the mechanical draftsman, and since many apparently widely different embodiments of this invention may be made within the scope of the accompanying claims without departing from the spirit and scope of the same, it is intended that all matter contained in the accompanying specification shall be interpreted as illustrative only and not in a limiting sense and I desire only such limitations placed thereon as justice dictates.

What I claim as my invention is:

1. A piston and high compression assembly positioned thereon embodying a compression ring having one edge thereof recessively chamfered and an annular spring pressed sleeve having one edge thereof bearing against said compression ring, the edge of said sleeve being chamfered similarly to said ring and a pair of freely mounted annular sleeves surrounding said piston and positioned between said compression ring and said sleeve, said sleeves being spaced apart by spring means and oppositely acting under the influence thereof such that the edge of one of said sleeves engages the chamfered edge of said ring while the other engages the chamfered edge of said sleeve.

2. A piston and high compression assembly positioned thereon embodying a compression ring having one edge thereof recessively chamfered, an annular freely mounted skirt upon said piston and spaced from said compression ring the edge of said skirt which opposes the chamfered edge of said ring being chamfered similarly to said ring, and a pair of freely mounted annular sleeves surrounding said piston and positioned between said compression ring and said skirt, said sleeves being spaced apart by spring means and oppositely acting under the influence thereof such that the edge of one of said sleeves engages the chamfered edge of said ring while the other engages the chamfered edge of said skirt.

3. A piston and high compression assembly positioned thereon embodying a compression ring recessively chamfered upon one edge thereof to provide an undercut cuneiform recess, and an annular spring pressed slidable sleeve having one edge thereof stepped outwardly from the inner surface of said sleeve to provide an annular projecting flange in engagement with said chamfered edge.

4. The piston and ring assembly according to claim 1 which includes a retaining ring provided with an annular groove and an oil ring in said groove.

5. A piston and high compression assembly positioned thereon embodying a pair of interlocking compression rings having adjacent and complementarily rabbeted edges, the remaining edge of one of said rings being recessively chamfered, and an annular spring pressed slidable sleeve having one edge thereof bearable against said recessively chamfered edge and movable in a plane parallel with the piston axis to force said ring outwardly against a surrounding cylinder wall.

6. A piston and high compression assembly positioned thereon, said high compression assembly embodying an intermediate annular split

skirt held in place by rings positioned in grooves formed in the wall of said piston, a split compression ring surrounding said piston and spaced from said skirt, said compression ring being recessively chamfered upon one edge thereof to provide an undercut cuneiform recess, said skirt being similarly chamfered upon both edges thereof, a retaining ring upon said piston and spaced from said skirt upon the opposite side thereof to that upon which said compression ring is positioned, a pair of freely mounted annular sleeves surrounding said piston and positioned between said compression ring and said skirt, said sleeves being spaced apart by spring means and oppositely acting under the influence thereof such that one of said sleeves engages said opposing recessively chamfered edges upon said compression ring and said skirt, and an additional annular spring pressed slidable sleeve between said retaining ring and said skirt having one edge thereof in engagement with the re-

maining recessively chamfered edge of said skirt, all for the purpose of urging said compression ring and said skirt outwardly against the associated cylinder wall under progressive conditions of wear.

5 7. A piston centering ring assembly, comprising in combination, a compression ring recessively chamfered at the rear of the external annular surface thereof, and a source of pressure 10 acting against said chamfer parallel to the axis of said piston and uniformly around the circumference of said ring to force said ring outwardly against a surrounding cylinder wall.

15 8. In combination with the device as defined in claim 7 a groove-forming ring receivable into a shallow annular groove in said piston, said groove-forming ring projecting beyond the adjacent external piston surface to form one removable wall of the groove for said compression ring.

20 DAVID BUSHBY.
